CHAIR

Thomas Winrow, 530 S. Sleight,
Naperville, Ill. 60540

Filed Apr. 22, 1971, Ser. No. 136,649

Term of patent 14 years

Int. Cl. D6—02

U.S. Cl. D6—26

The figure is a perspective view of a chair illustrating my new design.

The back of the chair is conventionally plain while the side not shown is substantially identical to the side shown.

I claim:

The ornamental design for a chair, as shown and described.
